(57) **CLAIM**

The ornamental design for a bicycle grip, as shown and described.

DESCRIPTION

FIG. 1 is a front perspective view of a bicycle grip showing my new design;

FIG. 2 is a rear side perspective view of the bicycle grip as shown in FIG. 1;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another right side elevational view, shown in an environment of use.

The dash-dash broken lines shown illustrate portions of the bicycle grip that form no part of the claimed design. The line-dash-dash broken lines showing the hand and portion of the bicycle handlebar arm in FIG. 9 illustrate environment that form no part of the claimed design.

1 Claim, 9 Drawing Sheets
